UNITED STATES PATENT OFFICE.

EMILY G. SKINNER, OF BUFFALO, NEW YORK.

DEVICE FOR DAMPENING AND FOLDING COLLARS.

No. 873,179.

Specification of Letters Patent.

Patented Dec. 10, 1907.

Application filed November 29, 1905. Serial No. 289,680.

To all whom it may concern:

Be it known that I, EMILY G. SKINNER, a citizen of the United States, residing at Buffalo, in the county of Erie and State of New York, have invented certain new and useful Improvements in a Device for Dampening and Folding Collars, of which the following is a specification.

My invention relates to a device for dampening and folding collars, and more particularly to a device for dampening and folding a wing-point collar on the fold-line.

The object of this invention is the production of a simple, inexpensive, and effective device of this character in which provision is made to dispense with "false-movements", by which is meant useless movements and work brought on by the arrangement and operation of the machines for this purpose now in use.

My invention is designed to dampen the surface of the wing-point of a collar as well as the fold-portion thereof, and permit simultaneous folding of the point; thus preparing the collar for the wing-point ironer, to which this device may be attached or located in close proximity thereto so that the collars may be finished when dampened and turned, without removing from the hands.

Another object of my invention is to so construct the device that the button-hole tabs of the collar are held out of contact with the device so that they need not again be subjected to the ironing process.

Still further objects are to subject the surface of the wing-points to a comparatively slight moistening action, while the fold of the collar is subjected to a proportionately greater moistening action; thus assuring the proper turning of the wing-point without liability of cracking the collar; to provide means to permit the folding of collars of all styles and sizes of wing-points, and to otherwise improve on collar dampeners and folders now in use.

With these objects in view, my invention consists in the construction, arrangement, and combination of parts to be hereinafter described and particularly defined in the appended claims.

Referring to the drawings.—Figure 1 is a perspective view of my improved device. Fig. 2 is a central vertical section of the same. Fig. 3 is a horizontal section taken on line

z—z, Fig. 2. Fig. 4 is a plan view of the casing which also serves as a pad support.

In order that the invention may be fully understood, I will now describe the same in detail, like numerals of reference referring to like parts in the several figures.

The reference numeral 5 designates a steam-chamber having a laterally entering steam inlet-pipe 6 provided at its inner end with a restricted port 7 of a size to permit the entrance of the proper quantity of steam into the steam-chamber. The latter is of a comparatively small diameter, and the steam issuing through said port is directed at an angle to the length of the chamber, and strikes against the wall of the latter at a point opposite the point of entrance. At the lower end of the chamber a water-outlet 8 is provided into which is fitted a drain-pipe 9 having a restricted opening 10. A steam-outlet 11 is provided at the upper end of the steam-chamber, into which is fitted a pipe or nipple 12 entering the box or casing 13, which is preferably cast in one integral piece to avoid seams and the consequent packing of the same. Said casing is substantially of semi-cylindrical contour and comprises, a top wall 14, a bottom wall 15, a straight front wall 16, and side and rear walls merging into one semi-circular wall 17. The upper surface of the top wall is provided near its front edge with a groove 18 arranged parallel with said edge, and with a series of parallel grooves 19 arranged at right-angles to the groove 18 and preferably connecting therewith.

A series of perforations 20 are formed in the upper wall and open into the groove 18. Similar perforations 21 are formed in said wall and open into several of the grooves 19, said perforations 21 being arranged in diagonal rows for a purpose to appear hereinafter. As shown in Fig. 4, the top wall is imperforate directly above the inlet of the casing and the steam coming in contact therewith at this point, is consequently diffused and escapes through perforations 20, 21.

A pad or cover 22 of absorbent material, such as cotton, felt, etc., is placed over the casing and is secured to the latter by a combined clamp and fold-device 23, comprising a fold-plate 24 semi-circular, or substantially so, in contour, and having depending lips 25 which are soldered or otherwise secured to a

clamping-band 26 surrounding the casing and the pad 22. Said band serves to securely clamp the pad to the casing and may be adjusted on the casing so that a space 27 5 of the desired size may be provided between said pad and the fold-plate 24, into which the wings of the collars are thrust. The clamping-band has its ends terminating in outstanding ears 28 through which is passed 10 a clamping-screw 29, for drawing the band firmly around the casing with the pad between the two. By moving the clamping-band vertically on the casing, the space between the pad and fold-plate may be varied, 15 to meet the requirements of the different collars. It is to be noted that for turning wing-point collars, the front edge of the fold-plate is straight, and preferably parallel with the straight front side of the casing; said edge 20 being positioned above and slightly in rear of the perforations 20.

In order to make the device as small and compact as possible, yet provide for the dampening and folding of the wing-points of 25 different sizes, the fold-plate is separated from the clamping-band, except at points where the lips 25 are located which serve to support and maintain the fold-plate in proper relation to the clamping-band. By 30 this arrangement the points of all wings larger than the average may project at the rear of the casing through the opening between the fold-plate and the clamping-band, while permitting the fold-line to be brought 35 into proper position with reference to the folding edge of said plate.

The steam entering the steam-chamber, strikes the wall of the latter opposite the inlet thereof and passes up into the casing, 40 issuing therefrom through the perforations therein, and saturating or moistening the pad or covering 22 to the desired extent. By reason of the perforations 20 being arranged close together and in a direct line, a 45 small quantity of steam issues through the pad or covering on said line and comes in contact with the fold-line of the collar; said pad or covering being moistened to a greater extent at this point than at other points. 50 The steam condensing, fills the grooves and serves to maintain the pad or covering in a moist condition. The water of condensation drips back into the steam-chamber, and by reason of the steam entering said chamber at a right-angle to the flow of the water of condensation through the same, the water drops to the bottom of the chamber without being retarded by the steam. The steam 55 rises within the chamber without carrying the water with it, thus avoiding undue moistening of the pad or covering.

By arranging the perforations 21 in diagonal rows, assurance is had that the pad or covering is moistened at all times over an 60 area conforming to the triangular shape of

the wings of collars; and that the wings are properly dampened irrespective of their size. The button-hole tabs project over the sides of the device and are therefore held out of contact with the dampening-pad. 70

In operation, the collars which have been ironed preparatory to folding or turning the wings, are arranged within convenient reach of the operator. Successively they are taken up, and the wings thereof thrust underneath 75 the fold-plate to bring the fold-line to the edge of said plate and over the apertures 20; the collar is then turned over the edge of the plate and without removing from the hands is placed on a wing-ironer for the finishing 80 touches. When thrust under the fold-plate, the wing of the collar is moistened to the desired degree by contact with the pad or covering 22; and along the fold-line it is subjected to a greater moistening action to 85 permit of its being turned over the edge of the plate without liability of cracking.

The arrangement herein shown may be extended for turning "fold" or "turn-over" 90 collars and other starched and ironed articles, and I therefore wish to be understood, that changes may be made in the size thereof, without departing from my invention or sacrificing any of the advantages thereof, so that starched and ironed articles of all kinds 95 may be turned.

Having thus described my invention, what I claim is,—

1. A device for dampening and folding collars, comprising a casing having a steam 100 inlet and a series of steam-escape apertures, a covering of absorbent material for said casing, a fold-plate above said casing and separated therefrom by an intervening space, and means to support said fold-plate and simultaneously hold said absorbent material 105 on the casing.

2. A device for dampening and folding collars, comprising a casing having a steam-inlet and a series of steam-escape apertures, 110 a covering of absorbent material for said casing, and a combined fold and clamp-device consisting of a clamping-band to clamp the covering to the casing and a fold-plate supported by said clamping-band, said fold-plate having its fold-edge in proximity to 115 said apertures.

3. A device for dampening and folding collars, comprising a casing having a steam-inlet and its upper surface provided with 120 grooves and having also steam-escape apertures opening into said grooves, a covering of absorbent material for said casing, and a combined clamp and fold-device consisting of a clamping-band surrounding said covering to secure the same to the casing and a fold-plate positioned above said covering and supported by said clamping-band. 125

4. A device for dampening and folding collars, comprising a casing of semi-circular 130

contour and having its upper side provided with a groove adjacent to and parallel with the straight side of said casing and a series of parallel grooves arranged at right-angles 5 to the first mentioned groove, a series of apertures in the casing opening into said first mentioned groove, a second series of apertures in the casing arranged in diagonal rows and opening into said parallel grooves, 10 and a fold-plate supported on the casing and

arranged above said last mentioned grooves, said fold-plate being separated from said casing by an intervening space.

In testimony whereof, I have affixed my signature in the presence of two subscribing 15 witnesses.
